UNITED STATES PATENT OFFICE.

JOHN R. WILLIAMS, ALBERT D. STANLEY, AND JOSEPH S. ROGERS, OF GREENVILLE,
ALABAMA.

SHADE-ROLLER BRACKET.

Application filed February 27, 1925. Serial No. 11,986.

This invention relates to curtain fixtures and has special reference to a shade roller support.

It is common to secure brackets for shade rollers to the window casing either directly by screws or nails or to secure such fixtures to a block or board and fasten the latter to the casing by screws or nails. Either method results in marring the casing and makes considerable trouble when it is desired to paint the casing or remove the fixtures for any purpose.

One important object of the invention is to avoid these objections by the provision of an improved general construction of window shade bracket adapted to be readily applied to or disengaged from a window casing without the use of screws, nails or tools of any description.

A second important object of the invention is to provide an improved device of this description which may be applied to any size of window casing without adjustment of parts, the device itself being constructed without having sliding extensions and the like with their accompaniment of fastening bolts or screws.

A third important object of the invention is to provide an improved device of this class which can be cheaply made and in which the number of parts will be but few.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a front view of the invention showing a window casing in dotted lines.

Figure 2 is a front view showing the device as applied to a window casing having wider side and top members.

Figure 3 is a front view of the device to a larger scale than Figures 1 and 2.

Figure 4 is a side elevation thereof.

Figure 5 is a section through one end of the coiled spring used herewith on a greatly enlarged scale.

Figure 6 is a view showing the prongs on the upper part of the device.

In the embodiment of the invention here-
in disclosed there is provided a main part
preferably stamped from sheet metal. This
part consists of a vertical stem 10 having
intermediate its ends a short flange 11 pro-
vided with a suitable slot or opening 12 for
the reception of the pintle of the shade roller.
It is obvious that these devices are to be sup-
plied in pairs, one being for the right and
the other for the left side of the window.
Correspondingly the openings 12 will be
made to accommodate the shapes of the pintles.
At the top of the member 10 is a rearwardly
extending horizontal flange 13 provided at
its rear corners with prongs 14. At the bot-
tom, the member 10 is rolled to form a tube 70
15 wherethrough passes a coiled tension
spring 16, the middle portion of the spring
engaging in said tube and the ends extend-
ing equally on each side thereof. In each
end of this spring is secured (by brazing
or the like) a rod 17 having an end extend-
ing from the spring in continuation thereof
and provided with a terminal grip portion
18 extending at a right angle to the project-
ing end of the rod 17.

In applying the device the flange 13 is
engaged on top of the lintel of the window
and the spring stretched till the grips 18
can engage on the side edges of the window
side frame member.

The spring may be stretched so that both
ends lie in alinement for windows having
narrow lintels as in Figure 1, or the spring
ends may be bent down as in Figure 2 in
cases where the depth of the lintel is too
great to permit engagement of the grips
with the side edges of the frame while the
ends of the spring are alined. This feature
of the invention is very important as it en-
ables the device to be used with practically
all depths of lintels and all widths of side
members.

Also it will be noted that all of the parts,
which are only four in number, are fixedly
connected.

There has thus been provided a simple
and efficient device of the kind described
and for the purpose specified.

It is obvious that minor changes may be
made in the form and construction of the
invention without departing from the ma-
terial spirit thereof. It is not, therefore, de-
sired to confine the invention to the exact

form herein shown and described, but it is desired to include all such as properly come within the scope claimed.

Having thus described the invention, what is claimed as new, is:

- 5 1. A shade roller bracket formed from a single piece of sheet metal and including a body portion provided with a shade roller pintle engaging portion and having a flange at its upper end engageable over the top of a window lintel and having a transversely extending tube at its lower end, a coiled tension spring extending through said tube and gripped at the middle thereby, and side frame gripping members carried by the ends of said spring.
- 10 2. A shade roller bracket formed from a single piece of sheet metal and including a

body portion consisting of a vertical strip of sheet metal, a short flange on one edge 20 of the strip intermediate its ends and having a pintle receiving opening a rearwardly extending flange at the upper end of said strip and provided with prongs at its rear corners, a rolled portion at the lower end 25 of the strip forming a tube, a coiled tension spring extending through the tube and having its middle gripped thereby, and rods each secured in a respective end of said spring and having a projecting end bent at 30 right angles to form a grip.

In testimony whereof we affix our signatures.

JOHN R. WILLIAMS.
ALBERT D. STANLEY.
JOSEPH S. ROGERS.
